UNITED STATES PATENT OFFICE.

JESSE G. YEAGER, OF SPRING CITY, PENNSYLVANIA, ASSIGNOR TO THE
YEAGER-HUNTER SPRING CITY STOVE WORKS, OF SAME PLACE.

DESIGN FOR A COOKING-STOVE.

SPECIFICATION forming part of Design No. 30,287, dated February 28, 1899.

Application filed January 27, 1899. Serial No. 703,619. Term of patent 7 years.

To all whom it may concern:

Be it known that I, JESSE G. YEAGER, a citizen of the United States, residing at Spring City, in the county of Chester and State of Pennsylvania, have invented and produced a certain new and useful Design for a Cooking-Stove, of which the following is a specification, reference being had to the accompanying drawing, forming part hereof, and wherein a cooking-stove showing my design is illustrated in perspective.

As shown in the drawing, the leading or material feature of my design consists in the peculiar scrollwork ornamentation of the base, doors, shelf-support, and other parts of the stove.

The ornamentation of the base A consists of the two double scrolls $a\ a$, longitudinally arranged and oppositely coiled or convoluted from a point approximately at the longitudinal center of the apron of the base. Intertwined with each double scroll $a\ a$ and midway thereof is a single scroll a' . From the scrolls $a\ a$ and the scrolls $a'\ a'$ extend leaf-like ornamentations a^2 . Each foot A' of the base is ornamented with scrolls a^3 , leaves a^4 , and a lower double oppositely-arranged scroll a^5 , from which projects a three-pointed leaf a^7 . Surmounting the base is a plain band a^6 . The oven-door B consists of a central circular panel b, forming the end coil of a single scroll b'. Below the panel b and scroll b' are arranged the scroll ornamentations b^2 and b^3 , the latter consisting of two or more intertwined scrolls. Above the panel b are arranged two oppositely-arranged scrolls $b^4\ b^4$, corresponding to the scrolls $a\ a$ of the base and intertwined with the scroll ornaments b^2 and b^3 .

The fire-door C has two sets of scroll orna-

mentations, the upper set c being longitudinally and oppositely arranged in correspondence with the scrolls $a\ a$ of the base, whereas the lower set c' are vertically and oppositely arranged to form a conventional letter "X." 45

The ash-pit door D has a scroll ornamentation consisting of a central scroll d, from which extend longitudinally the two oppositely-arranged and longitudinal scrolls $d'\ d'$, each of which terminates in a vertical scroll d^2 . 50

The mantel-shelf support E has a central portion which is ornamented with three sets of scrolls, the upper set e being oppositely arranged to correspond with the upper set e of the fire-door C, and the lower set e' being arranged to form a conventional letter "X" 55 to correspond to the lower set c' of said fire-door. Intermediate of these two sets e and e' is a third set e'', arranged to form a conventional heart-shaped ornament. The central 60 portion of the support E is supported on each side by open scrollwork e^3 . Above the mantel-shelf E' is arranged a ledge e^4 , having a scrollwork design in conformity with the design of the mantel-shelf support E proper. 65

All the other parts of the stove are ornamented in keeping with the ornamentation of the parts hereinbefore enumerated.

Having thus described my invention, what I claim as new, and desire to secure by Letters Patent, is—

The design for a cooking-stove, substantially as herein shown and described.

In testimony whereof I have hereunto set my signature in the presence of two subscribing witnesses.

JESSE G. YEAGER.
